[76] Inventor: **Frank Prineppi**, 521 S. Andrews Ave., Suite 2, Fort Lauderdale, Fla. 33301

Primary Examiner—Kay H. Chin
Attorney, Agent, or Firm—Joseph Zallen

[**] Term: 14 Years

[57] **CLAIM**

[21] Appl. No.: 773,078

The ornamental design for adjustable universal handle for lifting objects with parallel or crossover straps, as shown and described.

[22] Filed: Oct. 8, 1991

DESCRIPTION

[52] U.S. Cl. D8/316; D34/28;

D3/30.1

[58] Field of Search ..... D34/28; D3/30.1; D8/316, DIG. 1, 300, 303; 16/114 R, 111 R, 112; 40/642; 190/116; 294/167

FIG. 1 is a right perspective view of an adjustable universal handle for lifting objects with parallel or crossover straps showing the handle arranged for parallel straps, the broken lines are for illustrative purposes only and form no part of the claimed design;

FIG. 2 is a right side elevational view thereof, the left side view being the same;

FIG. 3 is a left perspective view thereof showing the handle arranged for cross-over straps;

FIG. 4 is a left side elevational view of FIG. 3, the right side view being the same; and,

FIG. 5 is a bottom plan view of FIG. 3.
